UNITED STATES PATENT OFFICE.

JOHN A. MILLIKEN, OF AMBLER, PENNSYLVANIA, ASSIGNOR TO JOHN E. MARSDEN,
OF ATLANTIC CITY, NEW JERSEY.

GLASS-CUTTING MACHINE.

Original application filed August 21, 1916, Serial No. 116,170. Renewed March 25, 1921, Serial No. 455,593. Original No. 1,402,457, dated January 3, 1922. Application for reissue filed August 21, 1923. Serial No. 658,652.

This invention is a machine for cutting or grinding ornamental designs into the surfaces of glass articles, such as tumblers and the like.

- 5 One of the objects of the invention is to provide a machine of this character for automatically applying a design to the surface of the article being acted upon. A further object is to provide means for automatically 10 imparting a step by step rotation to the glass article, and for automatically applying a portion of the design during the pauses in the rotation thereof. A further object is to provide an automatic machine for ornamenting the surfaces of glass articles, said machine having means by which the design may be varied. A further object is to provide a machine of this character having means for controlling the cutting mechanism 15 20 to automatically compensate for inequalities in the surface of the glass articles. A further object is to provide means to engage the glass article and mechanism controlled thereby, to insure a uniform depth of cut by 25 the cutting mechanism. A further object is to provide means by which the depth of cut may be varied. A further object is to provide means whereby the machine will automatically adjust itself to glass bodies of different diameters, without previous manual 30 manipulation. A further object is to provide means whereby the machine will be automatically stopped at the completion of the design that is being imparted to the article being operated upon.
- 35 The invention will be hereinafter fully set forth and particularly pointed out in the claims.
- In the accompanying drawings:—
- 40 Fig. 1 is a side elevation of a machine constructed in accordance with the invention. Fig. 2 is a front view thereof. Fig. 2^a is a detail view of the yieldable abutment. Fig. 3 is a rear view of the machine. Fig. 4 is a 45 sectional side elevation, one of the sides of the machine frame being removed. Fig. 5 is a detail view of the chuck-rotating and the throw-off mechanisms. Fig. 6 is a detail view illustrating the means for preventing 50 rotation of the chuck. Figs. 7, 8, 9 and 10 are detail views of the feeler slide and grinder slides and their adjuncts. Fig. 11 is a longitudinal sectional view of the chuck and chuck shaft. Fig. 12 is a front end view of the chuck. Fig. 13 is a detail view of the 55 operating cam. Figs. 14 to 17, are diagrammatic views illustrating the method of cutting and various designs produced thereby.
- Referring to the drawings, 10 designates a base plate, attached to and supported by a 60 suitable bench or standard (not shown). Secured to said base plate 10, are the sides 11, of the frame, said sides being rigidly retained in spaced relation, by pairs of cross bars. The lower cross-bars 12 rest upon ribs 65 13, formed on the inner faces of said sides, said cross bars being held in position in suitable manner. The upper cross bars 15, have their ends in engagement with the inner faces of the sides 11, said bars 15 being arranged in different planes.
- The main drive shaft 16, is mounted in a sleeve-like bearing 17, extending transversely through one of the sides 11, a portion of said shaft being provided with a worm 18. 75 Power may be applied to the shaft in any suitable or preferred manner. In the drawings, a pulley 19, is illustrated as loosely mounted upon said shaft, said pulley receiving its power from a source, not shown. 80 Any desired form of clutch may be employed for coupling the pulley 19, with the drive-shaft. As shown in the drawings, the shaft is provided with a clutch member 20, rigidly secure thereto, complementary to a corresponding clutch member on one face of the pulley 19, a spring 21, encircling the shaft 16 acting against said pulley to normally 85 separate the clutch members. For the purpose of moving the pulley against the tension of spring 21, to effect engagement of the clutch members, a lever 22 is provided, the same being attached to a hub 23, rotatably mounted upon the shaft 16, one end of said hub being positioned to abut against the hub 90 of the pulley 19, the other end of the hub 23 being provided with a projection 24, shaped to enter a cam recess 25, formed in the contiguous end of the bearing sleeve 17. The spring 21, acts against the lever 22, to maintain the projection 24, opposite the recess 25, thereby permitting the spring 21 to move the pulley 19, in a direction to disengage the clutch. Mounted in suitable bearings with 95 100

which the cross-bars 15 are provided, is a cam shaft 27, the same being provided with a worm wheel 28, meshing with the worm 18 on the main drive shaft.

5 The cross bars 15 are provided with bearings which rotatably support a normally inclined chuck-shaft 30, provided with a ratchet wheel 31, which is engaged by a pawl 32, pivotally mounted upon a pawl carrier 33, slidably mounted upon a guide 34, secured in suitable manner to one of the cross-bars 15. The pawl carrier 33, is reciprocated by means of an arm 35, to which it is pivotally connected, said arm being attached 10 to a rock shaft 36, having its ends mounted in suitable bearings carried by the sides 11, said rock shaft being provided with an actuating finger 37, overhanging a cam member C secured to the cam shaft 27. Said cam member is provided with a plurality of raised peripheral cam portions 38, positioned to engage the finger 37, and thereby rock the shaft 36, so as to actuate the pawl member, whereby the chuck shaft received a 15 partial forward rotation. The chuck shaft 30, is slidably longitudinally in its bearings, movement being imparted thereto by means of a bell crank lever 39, one arm of which is provided with a fork 39^a, engaging 20 shoulder 40 formed on said shaft, the other arm of said bell crank lever being connected with a treadle 41. A spring 42, or other suitable device, is employed to press said chuck shaft upwardly against a spacing 25 bar 43, supported in a suitable carrier 44, attached to one of the bars 15, said spacing bar being positioned to engage an annular flange 45 attached to the shaft 30, to limit 30 longitudinal movement of said shaft in one direction, for a purpose to be hereinafter described. In order to lock the chuck shaft after each partial forward rotation thereof, under the action of pawl 32, a locking wheel 46 is rigidly secured thereto, the periphery 35 of said wheel being provided with V-shaped notches 47 corresponding in number with the teeth upon ratchet wheel 31. Said notches are engaged by a locking member 48, provided with a projection complementary thereto, said locking member being pivotally supported by a projection 49, attached to 40 one of the cross bars 15, a spring 50 acting to maintain said locking member normally in engagement with the periphery of the locking wheel.

45 The spacing bar 43 is provided with one or more shoulders 51, corresponding to the number of times the glass is to be completely rotated while the design is being applied thereto, said shoulders being positioned to be engaged by the flange 45. Attached to said flange 45 is a cam 52, which as the flange 45 completes each revolution, engages one of the shoulders of the spacing bar, and moves said 50 bar upwardly a sufficient distance to bring

the next shoulder into position opposite to said flange 45, the spring 42, on the treadle 41, serving to move the chuck shaft longitudinally to bring said collar into engagement with the said next shoulder.

55 Any desired form of chuck for engaging and holding the glasses to be operated upon, may be employed. In the form of chuck illustrated, the chuck shaft 30 is made hollow, and extending longitudinally through the 60 same is a draw-bar 53, provided at its lower end with a collar 54, slidably mounted upon the chuck shaft, and held in engagement with the fork 39^a, of the bell crank lever 39, by means of a spring 55, acting between 65 abutments upon said draw bar and said chuck shaft respectively. Rigidly secured to the upper end of the chuck shaft 30, are hubs 56 and 56' provided with pivoted fingers 57, which support glass engaging bars 58, of 70 approximate U-shape in cross section, an elastic band 59 encircling the bars 58 acting to maintain them normally under compression and in contracted relation. Each finger 57 is provided with a rearwardly extended 75 projection 60. The chuck shaft 30 is longitudinally slotted adjacent the hubs 56 and 56', to accommodate pins 61 and 61', attached to the draw bar 53. The pin 61 projects through a slotted portion 62, formed in 80 a slidably hub 63, said hub being provided with a flange 64, normally held against the projection 60, of the contiguous fingers 57, by means of springs 65, encircling bolts, or 85 similar devices 66, attached to said collar, and extended through lugs projecting from the hub 63. The pin 61 rigidly connects a hub 63' with the draw-bar 53, said hub 67 being provided with a flange 64', positioned 90 to engage the projections 60 of the fingers 57 carried by the hub 56'. By means of this 95 arrangement the flanges 64 and 64', acting against the projections 60, of the fingers 57 hold the bars 58, outwardly into engagement 100 with the inner surface of the glass to be 105 acted upon, and against the tension of the elastic band 59, until the treadle 41 is pushed downwardly, drawing the draw bar 53 110 downwardly, with the result that the hub 63' is positively moved at once with the draw-bar, permitting the fingers 57 carried by the hub 56', to move inwardly under the tension of the band 59, and as the draw bar 53 continues to move, the pin 61 will traverse the 115 length of the slot 62, and then withdraw the 120 hub 63 from engagement with the fingers 57 carried by the hub 56 whereupon a glass upon the chuck may be removed and a new one substituted. The arrangement above 125 described permits of the ready and prompt placing of the glass into, and removing it from position to be acted upon by the grinding devices to be hereinafter described, and at the same time insures that the glass will be firmly engaged at all points by a uniform 130

pressure of sufficient force to retain the same in position and insure its rotation with the chuck during the operations of the machine.

In the drawings two grinding mechanisms 5 A and B are disclosed, although either may be dispensed with without departing from the spirit of the invention. For most purposes, however, for which the invention is designed, two such mechanisms are desirable 10 the same being actuated by cams C and C' secured to cam shaft 27. Inasmuch as each of the mechanisms is a duplicate of the other, the description of one will suffice. Each of said grinding members comprises a 15 drive shaft 68 mounted in front and back slides 69 and 70, movably supported in housings 71 and 72, located at the front and back of the frame, respectively. Said housings are adjustably mounted upon guides 73, 20 carried by the contiguous side 11 of the frame, being connected by a top-plate 74, whereby both housings may be simultaneously moved to adjust the shaft 68, forwardly or backwardly, as may be desired. The 25 slides 69 and 70 are provided with anti-friction bearings of any suitable or desired form, capable of rotatably supporting said shaft. The housings 71 and 72 are provided with longitudinally extended slots 73^a, to 30 provide clearance for the lateral movement of the shaft when the slides 69 and 70 are actuated. A rock shaft 75 is supported by bearings 75^a, carried by the sides 11, and secured to said rock shaft are arms 76 and 35 77, which arms are provided with bearings 78, to support a second rock shaft 79, provided at its ends with crank members 80, engaging blocks 81 mounted in vertical guides 82, in the respective slides 69 and 40 70. Loosely mounted on the rock shaft 75 is one member 83, of a friction device, the other member 84 of which is connected with the arm 76. The member 83 of the friction device is secured to an arm 86 which engages 45 a cam groove 87 in one face of the cam member C or C', as the case may be. The shaft 68 is rotated in suitable manner, belt pulleys 68^a for that purpose being illustrated in the drawings.

50 The front face of the housing 71 is provided with a guide for a feeler slide 88, provided with a projection 89 adapted to engage the glass being operated upon, for the purpose of controlling the movement of the slides 69 and 70, said slide 88 having a slot 90 to provide clearance for the shaft 68. The inner face of the feeler slide 88, is provided with a pin or lug 91 which projects into a recess 92, in the slide 69, the movement 55 of the lug 91 relative to the slide 69 being adjustably limited by means of a screw 93, carried by the said slide 69, and supported opposite the pin or lug 91. When a glass is to be placed upon the chuck, the 60 rock shaft 79 is manually actuated by means of the finger 94, so as to move the slides 69 and 70, and the feeler slide 88, away from the chuck. When the glass has been placed in position, movement of the rock shaft 79 is reversed until the projection 89, comes 65 into contact with the glass, whereupon movement of all the slides is arrested. In order to temporarily lock the feeler slide 88, during the period that the chuck is not rotating, the housing 71 is provided with a 70 guide to receive a locking member 96 loosely mounted upon an eccentric 97 provided with an operating arm 98, connected by a link 99, with an actuating member 100, pivotally supported in an arm 101 carried 75 by one of the cross bars 12, and said actuating member being operatively connected with the cam C'. In operation after the feeler slide has been moved into engagement with the glass, the arms 76 and 77, are 80 actuated to move the slides 71 and 72, toward the chuck to bring the grinding wheels A and B into contact with the glass, the contacting movement of each wheel being arrested when the screw 93 comes 85 into contact with the pin or lug 91, movement of the feeler slide being prevented by the locking member 96. It will thus be observed that the feeler slide serves as a gage 90 to control the movement of its respective grinding wheel with respect to the tumbler. In order to prevent shaft 79 from rocking too freely a tension device is provided, such as the weight 94^a. Movement of the feeler slide 88 away from the chuck is adjustably 95 limited by a threaded rod 88^a mounted in slide 88 and positioned to engage a stop 88^b carried by slide 69.

100 In order to compensate for inequalities in the diameter of the glass being acted upon so as to insure uniformity in the operation of the grinding mechanism, the arm 76 is provided with an extension 103 provided at its extremity with a hub 104, carrying a sleeve 105, through which extends a pin 106. Said pin is encircled by a helical spring 107, one end of which acts against an abutment in the sleeve, and the other end acts against a collar 108 attached to the pin. Movement of the pin under the action of the spring is limited by the nut 109, movement in the other direction being limited by a flange 110 on the collar 108, positioned to abut against the end of the sleeve. Mounted 110 in suitable bearings carried by the sides 11, is a rock shaft 111, provided with an actuating member 112, positioned to engage cam projections 113 on the cam member C. Loosely mounted on said rock shaft is a member 114, provided with a wedge-shaped portion 115, positioned to move between the inner end of the pin 106, and a pin or lug 116 projecting from the side 11, said member 114, resting by gravity against a pin 120 or lug 117, carried by an arm 118 rigidly 125

130

secured to said rock shaft. In operation, while the slides 69 and 70 are moving toward the glass to be operated upon, the arm 103 moves away from the side member 11, 5 permitting the spring 107 to project pin 106 toward said side member, to move collar 110 away from the end of sleeve 105. At the same time the wedge portion 115 of member 114 is moving by gravity between pin 106 and lug 117. Just as soon as movement 10 of the slides is arrested, the movement of wedge member 115 is also arrested, for the reason that the gravity cannot overcome the friction of the engagement with pin 106. 15 The distance between collar 110 and the end of sleeve 105 at this time corresponds to the distance the slides 69 and 70 have moved toward the glass. As said slides move away from the glass, the extension 103 is first 20 moved the distance between collar 110 and the end of sleeve 105, whereupon the wedge 115, which fills the space between pin 106 and lug 116, acts as a solid abutment, co-operating with collar 110 to prevent further 25 movement of said extension 103, and therefore also limiting the withdrawal movement of the slides, but the cam arm is permitted to continue to move, by the friction device. By this arrangement each grinding wheel is 30 moved just far enough to clear the glass and permit the latter to be rotated, the grinding mechanism being then automatically held in a neutral position until the peak of the cam in member C or C', as the case may be, 35 comes around into engagement with the cam arm 86 to repeat the operation of the machine. This operation will be more clearly understood by reference to Fig. 13, in which the cam arm 86 is shown as having just 40 reached the peak of the cam. In travelling to this position, when the roller reaches the point *x*, the feeler slide 88 is unlocked, and the grinding wheel starts to withdraw, the withdrawal being completed when the point *v* is reached. 45 The roller must then travel from *v* to the peak of the cam, as indicated at *z*, further movement of the grinding wheel being prevented by the member 114 until the roller reaches the peak of the cam at 50 which point the cam 113 engages actuating member 112, and actuates rock shaft 111 to withdraw member 114, whereupon the operations of the machine are repeated. Thus it will be understood that the feeler 55 slide 88, serves as a gage to automatically adjust the parts to compensate for irregularities in the surface of the glass being acted upon, and also to automatically compensate for glasses of different sizes. 60 In order to provide for the automatic stopping of the machine at the completion of the cutting operation, suitable throw off mechanism is provided. Said mechanism is 65 illustrated as comprising a latch 120, slidably mounted in a boss attached to one of the sides 11, and normally held in the path of the clutch lever 22, by a spring 121. Said latch is shifted against the tension of the spring, by means of a lever 123, connected at one end to the latch, and pivotally supported in suitable manner, said lever having an extension by means of which it may be manually operated if desired. Adjustably attached to the chuck shaft 30 is a throw off pawl 126, movable with the chuck shaft 70 when the latter is shifted longitudinally. At the end of the last revolution of the chuck shaft, i. e., that revolution which takes place while the flange 45 is in engagement with the last notch of the spacing bar 43, 80 the throw-off pawl will have been moved into a position opposite the lever 123, and will engage a cam portion 127 on said lever, shifting the latter in a direction to withdraw the latch 120 from engagement with 85 the clutch lever 22, permitting the pulley 19 to be automatically unclutched from the drive shaft.

In operation, the operator first presses down upon the treadle 41, thereby shifting 90 the draw-bar 53, so as to contract the chuck, whereupon the glass may be placed over the chuck as shown at G in the drawing. Upon releasing the treadle, the chuck members will accurately and uniformly engage the glass 95 with sufficient force to insure that the glass will rotate with the chuck. Both shafts 79 are rocked toward the glass by the fingers 94, thereby bringing the feeler slides 88 into engagement with the glass, and moving the 100 grinding wheels also into engagement with the glass. The clutch lever 22 is then shifted to permit the pulley 19 to be clutched with the drive shaft 16, whereupon the cam shaft 27 is set in motion, the clutch lever 105 being engaged by latch 102. As soon as the cam shaft starts to revolve, the actuating member 100 is operated to bring the locking blocks 96 into engagement with the feeler 110 slides 88 to temporarily lock the latter rigidly against movement. Just as soon as the feeler slides 88 are locked, the cams C and C' rock the arms 86 to actuate the rock shafts 74 and 79, to carry the grinding wheels A and B into engagement with opposite sides of the glass, the feeding movement of the said grinding wheels being limited by the engagement of the adjustable abutments 93, engaging the pins 91, carried by the feeler slides 88. As soon as movement of the slides is arrested by the abutments 93, the cutting or grinding action of the grinding wheels A and B ceases, further movement of the cam arms 86, however, being permitted by the friction devices, in 115 order to allow the cams to rotate to the points at which the withdrawal of the cutting devices is to commence. Simultaneously with the feeding movement of the grinding wheels A and B, the rock shaft 111, 120

125

130

has been operated to permit the members 114 to drop between the pins 106 and the lugs 116, the distance between collar 110 and the end of the sleeve 105 corresponding to 5 the distance the slides have travelled toward the glass. When the cams C and C' have rotated to the point that the cam arms 86 are moved to withdraw the cutters, the member 100 is actuated to disengage the locking 10 blocks 96 from the feeler slides 88, and the reverse movement of the rock shafts 74 moves the grinding wheels A and B away from the glass, a sufficient distance to permit the latter to be rotated with the chuck. 15 By reason of the engagement between the pins 106, lugs 116 and the members 114, rigid abutments are provided which prevent the slides from moving back a distance greater than that required to permit of rotation of 20 the glass, the friction devices permitting the cam members 86 to move until the peaks of the cams C and C' come around into engagement therewith. Just as soon as the slides are moved to disengage the cutters from the 25 glass, the cam member C actuates the pawl carrier 33, so as to rotate the chuck shaft a predetermined distance. At the time that this rotation of the chuck shaft is completed, the peaks of the respective cam grooves in 30 cams C and C' have reached the cam arms 86, and the slides 69 and 70, and the feeler slides 88, are again moved toward the glass until the feeler slides engage the glass, when they are again locked, and the cutters 35 brought up into engagement with the glass, in the manner before described, the feeding movement being limited by engagement with the feeler slide, as before described. These 40 automatic operations of feeding up to and away from the glass, and the periodic rotation of the chuck shaft, continue until the chuck has completed a number of revolutions corresponding to the number of shoulders 51, on the spacer bar 43, the chuck being moved 45 longitudinally step by step at the end of each complete rotation of the chuck shaft. As the rotation of the chuck shaft in engagement with the last shoulder of the spacing bar is completed, the throw-off pawl 126 has been 50 moved to a position opposite the throw-off lever 123, whereupon the latch 120 is withdrawn from engagement with the clutch lever 22, and the pulley 19 is automatically unclutched from the drive shaft. The 55 treadle 41 is then depressed to contract the chuck, whereupon the glass may be withdrawn.

It will be understood that while the grinding mechanisms A and B, are illustrated and 60 described as mounted on horizontal shafts, with an inclined chuck shaft between them, it is obvious that the chuck shaft may be mounted horizontally and the other shafts in parallel relation, inclined with respect to the 65 chuck shaft without departing from the

spirit of the invention. This angular relation of the grinders and of the chuck shaft possesses an important advantage. It will be readily seen that the grinders of the respective mechanism A and B make cuts in 70 the glass at an angle to each other, which angle will vary with the relative angle of the chuck and the axes of the grinders. When the cutters are adjusted so that they engage the glass in line with a point corresponding to the intersection of the axis of the chuck shaft, with the axes of the grinders the cuts made by the cutters will intersect each other at the middle, as shown at D 75 in Fig. 14. By adjusting the mechanism A 80 backwardly, and the mechanism B forwardly in equal distance, the cuts may be made to intersect at various points or even to be slightly separated as indicated at E, Figs. 15 and 17, and by reversing this adjustment the 85 cuts will have the reverse appearance as indicated at F in said Fig. 16.

Having thus explained the nature of the invention, and described an operative manner of constructing and using the same, although without attempting to set forth all of the forms in which it may be made, or all of the forms of its use, the following is claimed.

What I claim is:

1. In a glass cutting mechanism of the character described comprising a chuck, a grinder, means for alternately moving the grinder into and out of engagement with an article to be operated upon, and a feeler member reciprocated to and from said article by corresponding movements of said grinder. 90
2. A glass cutting mechanism of the character described comprising a chuck, a grinder, means for alternately moving the 100 grinder into and out of engagement with an article to be operated upon, a feeler member reciprocated to and from said article by corresponding movements of said grinder, and means cooperating with the grinder 105 moving means by which the engaging movements of the grinder and feeler member may be variably arrested to conform to inequalities in the surface contour of the article. 110
3. A glass cutting mechanism of the character described comprising a chuck, a grinder, means for alternately moving the 115 grinder into and out of engagement with an article to be operated upon, a feeler member reciprocated to and from said article by corresponding movements of said grinder, and means for locking the feeler member after 120 it has been moved into engagement with the article. 125
4. An improvement in glass cutting mechanism comprising a chuck, a grinder, means for moving the grinder into and out of engagement with an article carried by said chuck, a feeler slide for contacting with an article carried by said chuck, whereby 130

5 said slide may be variably positioned in accordance with the size of the article, a locking block, means for automatically actuating said block to cause the same to periodically engage said slide, and means whereby movement of the grinder toward said chuck is limited by said slide.

10 5. A glass cutting mechanism of the character described comprising a chuck, a grinder, means for alternately moving the grinder into and out of engagement with an article to be operated upon, a feeler member reciprocated to and from said article by corresponding movements of said grinder, 15 means cooperating with the grinder moving means by which the engaging movements of the grinder and feeler member may be variably arrested to conform to inequalities in the surface contour of the article, whereby a 20 uniform depth of cut is maintained irrespective of the surface inequalities, and means for adjustably varying the depth of the cut.

25 6. An improvement in glass cutting mechanism comprising a chuck, a grinder, means for moving the grinder into and out of engagement with an article carried by the chuck, a feeler slide movable relative to the chuck and positioned to contact with an 30 article carried by said chuck, said grinder and said slide being normally free for relative movement, and means for periodically limiting the relative movement of said grinder and said slide.

35 7. A glass cutting mechanism of the character described comprising a chuck, a grinder, means for alternately moving the grinder into and out of engagement with an article to be operated upon, a feeler member 40 reciprocated to and from said article by corresponding movements of the grinder, said feeler member and said grinder being connected to have relative movement at all times, and adjustable means for variably 45 limiting said relative movement.

50 8. An improvement in glass cutting mechanism comprising a chuck, a grinder, cutter-carrying slides supporting the grinder and movable toward and from the chuck, a 55 feeler slide for contacting with an article carried by said chuck, and movable relative to the grinder carrying slides, and means for limiting the relative movement of the grinder carrying slides and the feeler slide.

55 9. An improvement in glass cutting mechanism comprising a chuck, a grinder, slides supporting the grinder and movable toward and from the chuck, a feeler slide for contacting with an article carried by 60 said chuck, and movable relative to the grinder carrying slides, and means for adjustably varying the relative movement of the grinder carrying slides and the feeler slides.

65 10. An improvement in glass cutting

mechanism comprising a chuck, a grinder, slides supporting the grinder and movable toward and from the chuck, a feeler slide for contacting with an article carried by said chuck, and movable relative to the grinder carrying slides, a lug projecting from one face of the feeler slide, and an abutment on one grinder slide positioned to engage said lug to limit relative movement of the grinder-carrying slides and the feeler slide. 75

11. An improvement in glass cutting mechanism comprising a chuck, a grinder, slides supporting the grinder and movable toward and from the chuck, a feeler slide for contacting with an article carried by 80 said chuck, and movable relative to the grinder-carrying slides, a lug projecting from one face of the feeler slide, and a threaded rod carried by one grinder slide and positioned to engage said lug to adjustably limit relative movement of the grinder-carrying slides and the feeler slide. 85

12. An improvement in glass cutting mechanism comprising a chuck, a grinder, slides supporting the grinder and movable toward and from the chuck, a feeler slide for contacting with an article carried by said chuck, and movable relative to the grinder-carrying slides, means for periodically locking the feeler slide, and means for limiting 90 relative movement of the grinder-carrying slides and feeler slides. 95

13. An improvement in glass cutting mechanism comprising a chuck, a grinder, slides supporting the grinder and movable 100 toward and from the chuck, a feeler slide for contacting with an article carried by said chuck, and movable relative to the grinder-carrying slides, a locking block, means for causing said locking block to periodically engage said feeler slide, and means for limiting the relative movement of the grinder-carrying slides and the feeler slide. 105

14. An improvement in glass cutting mechanism comprising a chuck, a grinder, slides supporting the grinder and movable toward and from the chuck, a feeler slide for contacting with an article carried by said chuck, and movable relative to the grinder carrying slides, a locking block for 110 said feeler slide, an eccentric for actuating said locking block, and means for limiting relative movement of the grinder-carrying slides and the feeler slide. 115

15. An improvement in glass cutting 120 mechanism comprising a chuck, a grinder, slides supporting the grinder and movable toward and from the chuck, a feeler slide for contacting with an article carried by said chuck, and movable relative to the grinder-carrying slide, a locking block for 125 said feeler slide, an eccentric engaging said locking block to actuate the same, an actuator for said eccentric, a cam for periodically operating said actuator, and means 130

for limiting relative movement of the grinder-carrying slides and the feeler slides.

16. An improvement in glass cutting mechanism comprising a chuck, a grinder, means for moving the grinder into and out of engagement with an article carried by said chuck, a feeler slide for contacting with an article carried by said chuck, whereby said slide may be variably positioned in accordance with the size of said article, means whereby movement of the grinder toward said chuck is limited by said slide, and means for limiting movement of the feeler slide away from said chuck.

17. An improvement in glass cutting mechanism comprising a chuck, a grinder, means for moving the cutter into and out of engagement with an article carried by said chuck, a feeler slide for contacting with an article carried by said chuck, whereby said slide may be variably positioned in accordance with the size of said article, means whereby movement of the grinder toward said chuck is limited by said slide, and an adjustable abutment for variably limiting movement of the feeler slide away from said chuck.

18. An improvement in glass cutting mechanism comprising a chuck, a rock shaft, grinding mechanism connected with the rock shaft and movable thereby toward and from the chuck, means for actuating the rock shaft, and means positioned to contact with the article and controlled by the variations in the surface inequalities of the article carried by said chuck to variably limit successive movements of the grinding mechanism toward said chuck.

19. An improvement in glass cutting mechanism comprising a chuck, a rock shaft having a predetermined arc of oscillation, grinding mechanism connected with the rock shaft and movable thereby toward and from said chuck, means for actuating the rock shaft, means controlled by the size of the article carried by said chuck to limit movement of the grinding mechanism toward the chuck, and relief means for permitting the rock shaft to complete its arc of oscillation when movement of the grinding mechanism toward the chuck is arrested.

20. An improvement in glass cutting mechanism comprising a chuck, a rock shaft, grinding mechanism, arms carried by said rock shaft, a second rock shaft in said arms, means connecting said second rock shaft with respect to the grinding mechanism to permit independent movement of the grinding mechanism with respect to the chuck, and means positioned to contact with the article and controlled by the variations in the surface inequalities of the article carried by said chuck to limit movement of the grinding mechanism toward the chuck.

21. An improvement in glass cutting

mechanism comprising a chuck, a rock shaft, grinding mechanism, arms carried by said rock shaft, a second rock shaft carried by said arms, means connecting said second rock shaft with the grinding mechanism to permit independent movement of the grinding mechanism with respect to the chuck, means whereby said second rock shaft may be manually actuated, and means controlled by the size of the article carried by said chuck to limit movement of the grinding mechanism toward the chuck.

22. An improvement in glass cutting mechanism comprising a chuck, a rock shaft, grinder carrying slides, arms carried by said rock shaft, a second rock shaft mounted in said arms, slidable blocks in said slides connected with the second rock shaft, and means controlled by the size of the article carried by the chuck to limit movement of the grinder-carrying slides toward the chuck.

23. An improvement in glass cutting mechanism comprising a chuck, a rock shaft, grinding mechanism connected with the rock shaft and movable thereby toward and from the chuck, a rotatable cam, an arm connected with the rock shaft and engaging said cam, and means controlled by the size of the article carried by said chuck to limit movement of the grinding mechanism toward said chuck.

24. An improvement in glass cutting mechanism comprising a chuck, a rock shaft, grinding mechanism connected with the rock shaft and movable thereby toward and from the chuck, a rotatable cam, an arm connected with the rock shaft and engaging said cam, means controlled by the size of the article on said chuck for limiting movement of the grinding mechanism toward the chuck, and relief mechanism for permitting said arm to move with said cam after movement of the grinding mechanism toward the chuck is arrested.

25. An improvement in glass cutting mechanism comprising a chuck, a rock shaft, grinding mechanism connected with the rock shaft and movable thereby toward and from the chuck, a rotatable cam, an arm connected with the rock shaft and engaging said cam, means controlled by the size of the article on said chuck for limiting movement of the grinding mechanism toward the chuck, and a friction device connecting said arm with said rock shaft to permit said arm to move with the cam after movement of the grinding mechanism toward the chuck is arrested.

26. An improvement in glass cutting mechanism comprising a chuck, a rock shaft, grinding mechanism connected with the rock shaft and movable thereby toward and from the chuck, a cam arm engaging said cam and provided with a friction member, a complementary friction member carried by said rock

- shaft, and means controlled by the size of the article on said chuck for limiting movement of the grinding mechanism toward the chuck.
5. 27. An improvement in glass cutting mechanism comprising a chuck, a grinder, means for moving the grinder into and out of engagement with an article carried by the chuck, means controlled by variations 10 in the dimensions of said article for limiting movement of the grinder toward the chuck, and means for preventing the grinder from moving away from the chuck a distance greater than the distance traversed by 15 it when moving toward the chuck.
28. An improvement in glass cutting mechanism comprising a chuck, a grinder, means for moving the grinder into and out of engagement with an article carried by 20 said chuck, a feeler slide for contacting with an article carried by said chuck, whereby said slide may be variably positioned in accordance with the size of the article, means whereby movement of the grinder toward 25 said chuck is limited by said slide, and means for preventing the grinder from moving away from the chuck a distance greater than the distance traversed by it when moving toward the chuck.
30. 29. An improvement in glass cutting mechanism comprising a chuck, a grinder, means for moving the grinder toward and from the work, means for variably limiting movement of the grinder toward the work in 35 accordance with inequalities in the surface of the work, and means for preventing the grinder from moving away from the work a distance greater than the distance traversed by it when moving toward the chuck in 40 making each individual cut.
30. An improvement in glass cutting mechanism comprising a chuck, a grinder, a rock shaft connected with the grinder to move the same into and out of engagement 45 with an article carried by the chuck, means for periodically actuating said rock shaft, means for variably limiting movement of the grinder toward said chuck in accordance with inequalities in the size of said article, 50 and means for preventing the grinder from moving away from the chuck a distance greater than the distance traversed by it when moving toward the chuck in making each individual cut.
55. 31. An improvement in glass cutting mechanism comprising a chuck, a grinder, a rock shaft connected with the grinder and having a predetermined arc of oscillation to move the grinder toward and from the 60 chuck, means for variably limiting movement of the grinder toward the chuck in accordance with inequalities in the article carried by said chuck, means for preventing the grinder from moving away from the 65 chuck a distance greater than the distance
- traversed by it when moving toward the chuck, and relief means for permitting the rock shaft to complete its arc of oscillation when movement of the grinder away from the chuck is arrested.
70. 32. An improvement in glass cutting mechanism comprising a chuck, a grinder, a rock shaft connected with the grinder to move the same toward and from the chuck, means for periodically actuating said rock shaft, means for variably limiting movement of the grinder toward said chuck in accordance with inequalities in the size of an article carried by said chuck, an arm attached to said rock shaft, and means co- 75 operating with said arm to limit movement of the grinder away from said chuck.
33. An improvement in glass cutting mechanism comprising a chuck, a grinder, a rock shaft connected with the grinder to move the same toward and from the chuck, means for periodically actuating said rock shaft, means for variably limiting movement of the grinder toward said chuck in accordance with inequalities in the size of an article carried by said chuck, an arm connected with said rock shaft, and a variable 80 abutment positioned to cooperate with said arm to limit movement of the grinder away from said chuck.
90. 34. An improvement in glass cutting mechanism comprising a chuck, a grinder, a rock shaft connected with the grinder to move the same toward and from the chuck, means for periodically actuating said rock shaft, means for variably limiting movement of the grinder toward said chuck in accordance with inequalities in the size of an article carried by said chuck, an arm connected with said rock shaft, and provided 95 with a variable abutment, and a wedge-shaped abutment positioned to cooperate with said variable abutment to variably limit movement of the grinder away from said chuck.
100. 34. An improvement in glass cutting mechanism comprising a chuck, a grinder, a rock shaft connected with the grinder to move the same toward and from the chuck, means for periodically actuating said rock shaft, means for variably limiting movement of the grinder toward said chuck in accordance with inequalities in the size of an article carried by said chuck, an arm connected with said rock shaft, and provided 105 with a variable abutment, and a wedge-shaped abutment positioned to cooperate with said variable abutment to variably limit movement of the grinder away from said chuck.
110. 35. An improvement in glass cutting mechanism comprising a chuck, a grinder, a rock shaft connected with the grinder to move the same toward and from the chuck, means for periodically actuating said rock shaft, means for variably limiting movement of the grinder toward said chuck in accordance with inequalities in the size of an article carried by said chuck, an arm connected with said rock shaft and provided 115 with a variable abutment, a pivoted member having a wedge-shaped abutment positioned to cooperate with said variable abutment to variably limit movement of the grinder away from said chuck, and means for controlling movement of said abutment.
120. 36. An improvement in glass cutting mechanism comprising a chuck, a grinder, a rock shaft connected with the grinder to move the same toward and from the chuck,
125. 130.

means for periodically actuating said rock shaft, means for variably limiting movement of the grinder toward said chuck in accordance with inequalities in the size of 5 an article carried by the chuck, an arm connected with said rock shaft, a wedge-shaped abutment, and means whereby said abutment automatically moves transversely of said arm as the arm moves with the rock 10 shaft during movement of the grinder toward said chuck.

37. An improvement in glass cutting mechanism comprising a chuck, a grinder, a rock shaft connected with the grinder to 15 move the same toward and from the chuck, means for periodically actuating said rock shaft, means for variably limiting movement of the grinder toward said chuck in accordance with inequalities in the size of 20 an article carried by the chuck, an arm carried by the rock shaft, and a pivotally supported wedge-shaped abutment positioned to move by gravity transversely of said arm as the arm moves with the rock shaft during 25 movement of the grinder toward said chuck.

38. An improvement in glass cutting mechanism comprising a chuck, a grinder, a rock shaft connected with the grinder to move the same toward and from the chuck, 30 means for periodically actuating said rock shaft, means for variably limiting movement of the grinder toward said chuck in accordance with inequalities in the size of an article carried by the chuck, an arm connected with the rock shaft, a pivotally supported wedge-shaped abutment positioned to move by gravity transversely of said arm as the arm moves with the rock shaft during 35 movement of the grinder toward said chuck, 40 and an actuator for reversing movement of said abutment.

39. An improvement in glass cutting mechanism comprising a chuck, a grinder, means for moving the grinder toward and 45 from the chuck, means for variably limiting movement of the grinder toward said chuck in accordance with inequalities in the size of an article carried by said chuck, and a variable abutment for preventing the grinder from moving away from the chuck a distance greater than the distance traversed by it when moving toward the chuck.

40. An improvement in glass cutting mechanism comprising a chuck, a grinder, 55 means for moving the grinder toward and from the chuck, means for variably limiting movement of the grinder toward said chuck in accordance with inequalities in the size of an article carried by the chuck, a wedge-shaped abutment, means cooperating with 60 said abutment for preventing the grinder from moving away from the chuck a distance greater than the distance traversed by it when moving toward the chuck, and means 65 for controlling movement of said abutment.

41. An improvement in glass cutting mechanism comprising a chuck, a grinder, means for moving the grinder toward and from the chuck, means for variably limiting movement of the grinder toward said chuck 70 in accordance with inequalities in the size of an article carried by the chuck, a gravity operated variable abutment, means cooperating with said abutment for preventing the grinder from moving away from the chuck 75 a distance greater than the distance traversed by it when moving toward the chuck, and an actuator for periodically positioning said abutment.

42. An improvement in glass cutting 80 mechanism comprising a chuck, a grinder, a rock shaft connected with the grinder and having a predetermined arc of oscillation to move the grinder toward and from the chuck, means for variably limiting movement of 85 the grinder toward the chuck in accordance with inequalities in the article carried by the chuck, an arm for operating said rock shaft, means cooperating with said arm to prevent the grinder from moving away from the 90 chuck a distance greater than the distance traversed by it when moving toward the chuck, and means for effecting a variable engagement between said arm and said rock shaft. 95

43. An improvement in glass cutting mechanism comprising a chuck, a grinder, a rock shaft connected with the grinder and having a predetermined arc of oscillation to move the grinder toward and from the 100 chuck, means for variably limiting movement of the grinder toward the chuck in accordance with inequalities in the article carried by said chuck, an arm for operating said rock shaft, means cooperating with said 105 arm to prevent the grinder from moving away from the chuck a distance greater than the distance traversed by it when moving toward the chuck, and complementary friction devices connecting said arm and said rock shaft. 110

44. An improvement in glass cutting mechanism comprising a chuck, a grinder, a rock shaft, an arm having a frictional engagement with said rock shaft and connected 115 with said grinder, said grinder being movable toward and from the chuck, means for variably limiting movement of the grinder toward the chuck in accordance with inequalities in the article carried by said chuck, an extension for said arm, and means cooperating with said extension to prevent the grinder from moving away from the chuck a distance greater than the distance traversed by it when moving toward the chuck. 120

45. An improvement in glass cutting mechanism comprising a chuck, a grinder, an arm for moving said grinder toward and from said chuck, said arm having an extension, means for variably limiting movement 130

of the grinder toward the chuck in accordance with inequalities in the article carried by said chuck, means cooperating with said extension to prevent the grinder from moving from the chuck a distance greater than the distance traversed by it when moving toward the chuck, and means for periodically actuating said arm.

46. An improvement in glass cutting mechanism comprising a chuck, a grinder, a cam, a cam arm engaging said cam, a relief connection between the cam arm and the grinder, means for variably limiting movement of the grinder toward the chuck in accordance with inequalities in the article carried by the chuck, and means for preventing the grinder from moving away from the chuck a distance greater than the distance traversed by it when moving toward the chuck.

47. An improvement in glass cutting mechanism comprising a chuck, a grinder, means for moving the grinder toward and from the chuck, an arm connected with the grinder-moving means, means for variably limiting movement of the grinder toward the chuck in accordance with inequalities in the size of an article carried by the chuck, a yieldable abutment carried by said arm, and means for engaging said abutment to limit movement of the grinder away from said chuck.

48. An improvement in glass cutting mechanism comprising a chuck, a grinder, means for moving the grinder toward and from the chuck, an arm connected with the grinder-moving means, means for variably limiting movement of the grinder toward the chuck in accordance with inequalities in the size of an article carried by the chuck, a yieldable abutment carried by said arm, and a variable abutment positioned to engage said yieldable abutment to limit movement of the grinder away from said chuck.

49. An improvement in glass cutting mechanism comprising a chuck, a grinder, means for moving the grinder toward and from the chuck, an arm connected with the grinder-moving means, means for variably limiting movement of the grinder toward the chuck in accordance with inequalities in the size of an article carried by the chuck, a yieldable abutment carried by said arm, a pivoted member having a wedge-shaped abutment positioned to engage said yieldable abutment to variably limit movement of the grinder away from the chuck, and means for controlling movement of said wedge-shaped abutment.

50. An improvement in glass cutting mechanism comprising a chuck, a grinder, means for moving the grinder toward and from the chuck, an arm connected with the grinder-moving means, means for variably limiting movement of the grinder toward

the chuck in accordance with inequalities in the size of an article carried by the chuck, a yieldable abutment carried by said arm, and a pivotally supported wedge-shaped abutment positioned to move by gravity transversely of said yieldable abutment during movement of the grinder toward said chuck.

51. An improvement in glass cutting mechanism comprising a chuck, a grinder, means for moving the grinder toward and from the chuck, an arm connected with the grinder-moving means, means for variably limiting movement of the grinder toward the chuck in accordance with inequalities in the size of an article carried by the chuck, a yieldable abutment carried by said arm, a pivotally supported wedge-shaped abutment positioned to move by gravity transversely of said arm as the grinder moves toward said chuck, and an actuator for reversing the movement of said wedge-shaped abutment.

52. An improvement in glass cutting mechanism comprising a chuck, a grinder, means for moving the grinder toward and from the chuck, an arm connected with the grinder moving means, means for variably limiting movement of the grinder toward the chuck in accordance with inequalities in the size of an article carried by the chuck, a spring pressed pin mounted in said arm and having abutment shoulders, and means for variably engaging said pin to limit movement of the grinder away from said chuck.

53. An improvement in glass cutting mechanism comprising a chuck, a grinder, means for moving the grinder into and out of engagement with an article carried by the chuck, means for rotating the chuck, and pattern controlled means for imparting a longitudinal movement to said chuck.

54. An improvement in glass cutting mechanism comprising a rotatable chuck, a grinder, means for moving the grinder into and out of engagement with an article carried by the chuck, means normally acting to impart longitudinal movement to the chuck, and pattern means for regulating said longitudinal movement.

55. An improvement in glass cutting mechanism comprising a spring pressed chuck shaft having a flange, a cutter, means for moving the cutter into and out of engagement with an article supported by said chuck shaft, pattern means engaging said flange to limit movement of said shaft under the action of its spring, and automatic means for disengaging said pattern means from said flange.

56. An improvement in glass cutting mechanism comprising a rotatable chuck, a grinder, means for moving the grinder into and out of engagement with an article carried by the chuck, means normally acting

to impart longitudinal movement to the chuck, a pattern member controlling said longitudinal movement, and means for automatically adjusting said pattern member to permit limited longitudinal movement of said chuck.

57. An improvement in glass cutting mechanism comprising a rotatable chuck provided with a flange, a grinder, means for moving the grinder into and out of engagement with an article carried by the chuck, means normally acting to impart longitudinal movement to the chuck, a pattern member engaging said flange to limit said longitudinal movement, and means for automatically adjusting said pattern member to permit limited longitudinal movement of said chuck.

58. An improvement in glass cutting mechanism comprising a rotatable chuck provided with a flange, a grinder, means for moving the grinder into and out of engagement with an article carried by the chuck, means normally acting to impart longitudinal movement to said chuck, a yieldable pattern member engaging said flange to limit said longitudinal movement, and a cam on said flange for periodically adjusting said pattern member to permit limited longitudinal movement of said chuck.

59. An improvement in glass cutting mechanism comprising a rotatable chuck, a grinder, means for moving the grinder into and out of engagement with an article carried by the chuck, a flange connected with said chuck, means normally acting to impart longitudinal movement to said chuck, a pattern member provided with a plurality of shoulders positioned to engage said flange to limit said longitudinal movement, and means for periodically moving the pattern member to permit said flange to successively engage said shoulders.

45. 60. An improvement in glass cutting mechanism comprising a rotatable chuck, a grinder, means for moving the grinder into and out of engagement with an article carried by the chuck, and means controlled by the chuck for automatically stopping the machine when the chuck has made a predetermined number of revolutions.

61. An improvement in glass cutting mechanism comprising a rotatable chuck, a grinder, means for moving the grinder into and out of engagement with an article carried by the chuck, pattern means controlling the operation of the chuck, and means for automatically stopping the machine when the pattern on said article has been completed.

62. An improvement in glass cutting mechanism comprising a rotatable chuck, a grinder, means for moving the grinder into and out of engagement with an article car-

ried by the chuck, a flange connected with said chuck, means normally acting to impart longitudinal movement to the chuck, a pattern member provided with a plurality of shoulders positioned to engage said flange to limit said longitudinal movement, means for periodically moving the pattern member to permit said flange to successively engage said shoulders, and means for automatically stopping the machine at the end of one complete revolution after the flange is engaged with the last shoulder.

63. An improvement in glass cutting mechanism comprising a drive shaft, a rotatable chuck, means operated by said drive shaft for actuating said chuck, means normally acting to impart longitudinal movement to the chuck, a throw-off member controlling the application of power to said drive shaft, and a throw-off pawl connected with the chuck and normally out of register with said throw-off member, said pawl being positioned to be brought into engagement with the throw-off member as the chuck moves longitudinally.

64. An improvement in glass cutting mechanism comprising spaced apart grinders mounted on parallel axes, and a chuck positioned between said cutters, on an axis extending in the same general direction, the axis of the chuck being at an angle with respect to the axes of the grinders.

65. An improvement in glass cutting mechanism comprising spaced apart grinders mounted on parallel horizontal axes, and a chuck located between the grinders and mounted on an inclined axis extending in the same general direction.

66. An improvement in glass cutting mechanism comprising spaced apart grinders mounted on parallel axes, a chuck positioned between said grinders, the axis of the chuck being at an angle with respect to the axes of the grinders, and means whereby the grinders may be adjusted in lines parallel with their axes.

67. An improvement in glass cutting mechanism comprising a frame, spaced apart grinder slides, grinders in said slides mounted on parallel axes, a chuck between the grinders, the axis of the chuck being at an angle with respect to the axes of the grinders, means for moving the grinder slides toward and from the chuck, and means whereby the grinder slides may be adjusted forward and rearwardly on said frame.

68. An improvement in glass cutting mechanism comprising a frame, spaced apart boxes, spaced apart grinders mounted in said boxes on parallel axes, a chuck between the grinders, the axis of the chuck being at an angle with respect to the axes of the grinders, and means whereby said boxes may be adjusted forwardly and rearwardly in said frame.

69. Glass cutting mechanism comprising spaced apart grinders mounted on axes disposed in a common plane, and a chuck located between said grinders and mounted 5 on an axis inclined with respect to said plane.

70. Glass cutting mechanism comprising a chuck, and two rotatable grinding discs each having an axis inclined with respect 10 to the axis of said chuck and arranged to simultaneously cut decorative figurements of different angularity on an article carried by said chuck, said grinding disks being mounted in positions which are normally fixed 15 with relation to the position of the chuck.

71. Glass cutting mechanism comprising a chuck, two grinders, and means for supporting said grinders in position to simultaneously cut decorative figurements of different angularity on an article carried by 20 said chuck, said grinder supporting means being in normally fixed positions relative to the position of said chuck.

72. Glass cutting mechanism comprising 25 a rotatable work holder, a plurality of grinders for operating on an article to be cut, and means for supporting each of said grinders for movement upon a surface of the article at an angle with respect to the line 30 of movement of the other grinder upon said surface, said grinding disks being mounted in positions which are normally fixed with relation to the position of the chuck.

73. Glass cutting mechanism comprising 35 a work holder for an article to be cut, and means for simultaneously cutting figurements of different angularity with respect to a line disposed circumferentially of the 40 article, said cutting means being supported in positions which are normally fixed with relation to the position of the work holder.

74. Glass cutting mechanism comprising a 45 shaft rotatable about a fixed axis, a chuck carried by said shaft, a locking wheel secured to said shaft, a locking device for said wheel, a ratchet wheel secured to the shaft, a pawl co-operating with said ratchet wheel to rotate the shaft, means for actuating 50 said pawl, and means controlled by said last named means for releasing said locking device.

75. Glass cutting mechanism comprising a shaft rotatable about a fixed axis, a chuck 55 carried by said shaft, a locking wheel secured to said shaft, a locking device for said wheel, a ratchet wheel secured to the shaft, a pawl co-operating with said ratchet wheel to rotate the shaft, means for actuating 60 said pawl, and means for simultaneously releasing said locking device and actuating said pawl.

76. Glass cutting mechanism comprising a shaft rotatable about a fixed axis, an 65 expandible chuck carried by said shaft, an op-

erating member for said chuck, a member 70 slidable axially of said shaft and rotatable therewith for controlling expansion and contraction of said chuck and an actuating device for said operating member having rotatable connection therewith.

77. A grinding machine comprising a frame, a rotatable chuck for gripping the article being cut mounted therein, means for causing step-by-step rotation of the 75 chuck, a slidable block mounted in the frame movable towards and from the chuck, a rotatable shaft journaled in the block, a grinder mounted on the shaft and adapted to contact with said article, and means for 80 moving said block to cause the grinder to contact with the article during the periods that the chuck is at rest and to maintain it out of contact during rotation thereof.

78. A grinding machine comprising a 85 frame, a rotatable chuck mounted therein, a block slidable towards and from the chuck, a shaft journaled in the block and having a grinder fixed thereto, a bell crank lever pivoted in the frame, one arm of which 90 has an operative engagement with the said block for actuating the same, and the other arm of which is resiliently urged in a direction to permit the block to cause the grinder to contact the article being cut, 95 and means for intermittently moving the second named arm in the opposite direction to cause separation of the grinder and said article.

79. A grinding machine comprising a 100 frame, a rotatable chuck mounted therein, a block slidable towards and from the chuck, a shaft journaled in the block and having a grinder fixed thereto, a bell crank lever pivoted in the frame, one arm of which has an 105 operative engagement with said block, for actuating the same, and the other arm of which is urged in a direction to permit the block to cause the grinder to contact the article being cut, and means for moving the 110 second named arm in the opposite direction to cause separation of said grinder and article, the two arms of the bell crank being connected by a lost motion connection.

80. A grinding machine comprising a 115 frame, a chuck for gripping the article being cut mounted therein, and having a step-by-step rotation, a slidable block, a cutter shaft journaled therein, a rock shaft upon said frame, a connection between said rock 120 shaft and block to move the cutter shaft toward and from the chuck, and means for oscillating said rock shaft in predetermined relation to said step-by-step rotation.

81. A grinding machine comprising a 125 frame, a chuck, a rock shaft mounted in the frame, grinding mechanism movable toward and from the chuck, an arm fixed to the rock shaft and connected to the grinding mechanism for moving the same, resilient means 130

- for urging the grinding mechanism towards the chuck, a rotatable cam, a second arm having a lost motion connection with the rock shaft engaging said cam, and means controlled by the size of the article on the chuck for limiting the movement of the grinding mechanism towards the chuck, the lost motion connection permitting the second arm to move with the cam after movement of the grinding mechanism towards the chuck is arrested.
82. Glass cutting mechanism comprising a frame, spaced apart grinders mounted in said frame, a chuck between the grinders, and means for adjusting the relative positions of said grinders axially of said chuck.
83. Glass cutting mechanism comprising a chuck for supporting an article to be ground and means for simultaneously cutting figurements on the article at different points axially thereof.
84. Glass cutting mechanism comprising a chuck for supporting an article to be ground, a plurality of cutters for operating on the article, means for imparting relative movement to said chuck and cutters for cutting figurements circumferentially of said article, and means for axially adjusting said cutters independently of one another.
85. Glass cutting mechanism comprising a chuck for supporting an article to be cut, a plurality of grinders, and means for positioning said grinders to simultaneously cut figurements of different angularity with respect to the axis of the article and at different points axially thereof.
86. Glass cutting mechanism comprising spaced apart grinders mounted on axes disposed in a common plane, a chuck located between said grinders and mounted on an axis

inclined with respect to said plane, and means automatically operable for intermittently moving said grinders toward said chuck.

87. Glass cutting mechanism comprising a chuck, rotatable grinding disks each having an axis inclined with respect to the axis of said chuck and arranged to simultaneously cut decorative figurements of different angularity on an article carried by said chuck, and automatic means for rotating said chuck only when said disks are free of said article, said grinding disks being mounted in positions which are normally fixed with relation to the position of the chuck.

88. Glass cutting mechanism comprising a chuck, means for automatically imparting intermittent rotative movement thereto, a plurality of grinders, and means for supporting said grinders in position to simultaneously cut decorative figurements of different angularity on an article carried by said chuck, said grinder supporting means being in normally fixed positions relative to the position of said chuck.

89. Glass cutting mechanism comprising a work holder for an article to be cut, means for simultaneously cutting figurements of different angularity with respect to a line disposed circumferentially of the article, and automatic means for intermittently rotating said work holder, said cutting means being supported in positions which are normally fixed with relation to the position of the work holder.

In testimony whereof I have hereunto affixed my signature this 10th day of August, 1923.

JOHN A. MILLIKEN.
